UNITED STATES PATENT OFFICE.

EDGAR W. CUNNINGHAM, OF JERSEY CITY, NEW JERSEY.

GLASS STRUCTURE.

SPECIFICATION forming part of Letters Patent No. 508,287, dated November 7, 1893.

Application filed June 30, 1893. Serial No. 479,240. (No model.)

To all whom it may concern:

Be it known that I, EDGAR W. CUNNINGHAM, of Jersey City, in the county of Hudson and State of New Jersey, have invented a new and useful Improvement in Glass Structures, 5 of which the following is a full, clear, and exact description.

My invention pertains to an improved construction of sky-lights and the roof and sides 10 of green-houses or conservatories and the like.

The invention consists in the novel construction and combination of the several parts, as will be hereinafter fully set forth and pointed out in the claims.

Reference is to be had to the accompanying drawings forming a part of this specification, in which similar figures and letters of reference indicate corresponding parts in all the views.

Figure 1 is a perspective view of opposing panels provided with the improved casing and illustrating the panels connected, the same view illustrating also the supports for the panels, one of the supports being in section.

Fig. 2 is a transverse section taken practically on the line 2-2 of Fig. 1. Fig. 3 is a longitudinal section, taken practically on the line 3-3 of Fig. 1. Fig. 4 is a detail perspective view of one of the binding strips. Fig.

5 is a similar view of another strip having a gutter formed integral with it; and Fig. 6 is a transverse section through panels provided with the casing strip shown in Fig. 5, said Fig. 6 likewise illustrating a vertical section 35 through one of the supporting beams and its cover.

The beams A and the caps B for the beams are of the ordinary construction, the beams being adapted to support the glass panels C, 40 and the cap plates being adapted to cover the upper portions of the beams, while the beams A are connected and braced by means of bars D of any approved construction.

The supporting beams A are practically of 45 inverted T-shape, and those employed preferably in connection with the plain casing strips shown in Fig. 4 are provided with gutters a, the gutters being produced in the head portions of the beams, one at each side of the shank or upright portion. The binding or casing strip E, shown in Fig. 4, is made of a spring material, as for example sheet brass,

and the material is bent upon itself to form an outer vertical straight wall 10, and is then bent downward at the top parallel with the inner side of the wall, forming a ridge 11; and finally the upper edge of the metallic strip is bent downward away from the outer straight wall 10, standing at more or less of an obtuse angle to said wall, and forming a longitudinal, 60 downwardly inclined flange 12.

The metal at the lower edge of the straight wall 10, is bent in like direction as the inclined flange 12, forming thereby a lower flange 13; but the lower flange is horizontal 55 and stands at an angle to the outer or straight wall. Thus the distance between the flanges 12 and 13 at their inner edges is less than the distance between them at their outer edges. The flange 12, is adapted to act as a shed, 70 since the edges of the glass panels are introduced between the flanges 12 and 13, of the binding or casing strips E, the edge of the panel being practically made to abut against the inner surface of the straight wall 10, as shown in both Figs. 1 and 2, while the upper flange 12 will engage firmly at its inner edge with the top or upper surface of the panel, engaging at no other point in its length, as is likewise shown in Figs. 2 and 6, thereby providing for more or less expansion and contraction of the glass, or of the beams A, or other supports for the panels when such contraction is in a vertical direction, while the elasticity of the entire binding strip will permit the panels to yield in any direction. It will also be noted that the inner angles of the cap, B, rest upon the sloping flanges, 12, and hence, when the cap is forced down by the nuts, 17, the said flanges are pressed upon 90 the panels with corresponding force, thus forming a closer contact than would otherwise exist.

When a binding or casing strip is placed upon the edge of a panel, the under flange 13 95 will engage throughout its length and width with the under surface of the panel. Thus when a panel is incased with the casing or binding strip E above described, and two panels are made to abut, as shown in Figs. 1 100 and 3, the straight walls 10 of the binding or casing strips are brought together and soldered, brazed, or connected in some equivalent manner, as shown at 14 in Fig. 3.

this manner the panels are connected much more expeditiously and economically than heretofore, and the panels while in connection with the framing of the structure when united in the manner above described, add materially to the structural strength.

Instead of making the flange 13 straight, as shown in Fig. 4, it may be shaped at its inner edge in such manner as to form a longitudinal gutter 13^a, but the flange 13 will be of the same width as the upper flange 12, the gutter being located out of the vertical plane of the upper flange. Consequently, when this form of the binding or casing strip is used, the metal from which the lower flange is to be made must necessarily be wider than when the form of binding or casing strip illustrated in Fig. 4 is to be produced.

When placing the panels incased as above set forth, their side edges are supported upon one horizontal member of the beams A, and when the gutter 13^a is omitted, the form of beam illustrated in Figs. 1 and 2, is preferably employed, in which the condensation gutters a are produced. The glass panels are connected through the medium of their binding strips in the manner above stated, but other supports may be provided for them in addition to the beams A, if in practice it is found desirable.

When placing the binding strips around the glass panels, the strips may be soldered together at their adjoining ends; and in the event the guttered beams A, are used to support the sides of the panels, the binding or casing strips located at the ends of the panels may be provided with gutters, as shown in Fig. 3, while the side strips will be constructed as shown in Fig. 4; but the side strips may likewise be provided with gutters as illustrated in Fig. 6, in which event the supporting beams A, are made of an inverted T-shape, but the members of the head section A' may be made perfectly straight and smooth.

The supporting beams are provided with the usual screws and lock nuts 16 and 17, and the said beams are adapted to receive the caps B heretofore referred to, which are shaped to

receive the vertical or shank sections of the 50 beams, and extend over the members of the head section, and consequently over the panels the required distance.

It will be observed that the rib 11 at the upper edge of the binding or casing strips 55 will effectually prevent any water from backing up against the shank member of the supporting beams, and that the flange 12 will fit so closely against the panel, the binding strip being made of spring metal, that water can 60 not possibly pass the flange and enter the binding strip. When placing the binding strips upon abutting ends of glass, as shown in Figs. 1 and 3, the rib 11 is omitted and the upper flange is preferably made straight, as 65 illustrated at e in Fig. 3, in order that there may be no obstruction to the passage of water over the connected panels.

Having thus described my invention, I claim as new and desire to secure by Letters 70 Patent—

1. In a glass structure, the combination, with two aligned panels, of the joining piece consisting of two like metal binding strips, E, the same having straight abutting sides which are 75 soldered together, and parallel flat upper and lower flanges which closely embrace the adjacent opposite ends of said panels, the lower flanges being extended and curved as specified, thus forming a gutter, as shown and de- 80 scribed.

2. In a glass structure, the combination, with a supporting beam which is guttered and of inverted T-shape, the cap, B, and means for adjusting the latter, of the elastic binding 85 strips for the panels, the same having a lower flange, the upwardly-projecting ridge, 11, and the downwardly- and outwardly-projecting upper flange, 12, as specified, the angles of said cap bearing upon the inclined upper flanges, 90 and thus serving, when forced down, to press said flange more closely upon the panel, as described.

EDGAR W. CUNNINGHAM.
